LLOYD L. WEAKLEY, OF QUINCY, FLORIDA

BACK BAND HOOK

Application filed January 5, 1931. Serial No. 506,723.

This invention relates to harness and more particularly to a back-band having an improved trace-engaging hook.

One object of the invention is to provide a back-band hook of such construction that it may be easily applied to a back-band and after being vertically adjusted thereon remain in a set position.

Another object of the invention is to so form the hook that, while it may be very easily adjusted upon the back-band, an anchor bar forming part of the hook and engaged by the back-band will be firmly gripped and the hook prevented from slipping out of its adjusted position upon the back-band.

Another object of the invention is to so mount the anchor bar that it may be swung into and out of position to cause the hook to be held in an adjusted position and permit the hook to be moved from one position to another without being detached from the back-band.

Another object of the invention is to permit the hook to be removed from the back-band when repairs or replacements are necessary without disconnecting the back-band from the harness.

The invention is illustrated in the accompanying drawings, wherein

Fig. 1 is a view in elevation showing the improved hook applied to a portion of a back-band.

Fig. 2 is a vertical sectional view taken on the line 2-2 of Fig. 1.

Fig. 3 is a view showing the hook in elevation with the anchor bar swung outwardly from the body portion of the hook and broken away.

Fig. 4 is a longitudinal sectional view through the anchor bar.

Fig. 5 is a side elevation of a modified form of anchor bar.

Fig. 6 is a fragmentary sectional view through an anchor bar having a modified form of core.

Fig. 7 is a section on line 7-7 of Fig. 6, and

Fig. 8 is a side elevation of another modified form of anchor bar.

This improved hook is to be applied to a back-band, a portion of which is shown in Figures 1 and 2 and indicated by the numeral 1 and it will be understood that one of the hooks is to be applied to each end portion of 55 a back-band.

The body portion 2 of the hook is formed of strong metal and intermediate its ends is formed with a depending arm 3 from which is struck a tongue bent longitudinally 60 to form a bill 4 which extends upwardly from adjacent the lower end of the arm and is curved longitudinally, as shown clearly in Figure 2, with its free end projecting beyond the inner face of the tongue in order to 65 prevent a trace from slipping upwardly out of engagement by this bill. A slot 5 extends longitudinally of the body and at one end of this slot the body is cut to form a strip which is disposed transversely of the 70 slot and bent outwardly to form an eye 6. The slot 5 is of sufficient width to permit a portion of the back band to be folded transversely upon itself, as shown at 7, and pass outwardly through the slot. By this arrangement the hook may be easily applied to a 75 back-band forming part of a harness without detaching the back-band from the harness.

In order to secure the hook in a set position upon the back-band, there has been provided an anchor bar 8. This anchor bar consists of an outer sleeve 9 which may be formed of wood, metal or any other desired material, as shown in Figures 2, 3, and 4, and a core 10 80 extending longitudinally through the sleeve. The core consists of a wire strand doubled intermediate its length to form an eye 11 having arms 12 extending therefrom for passage through the sleeve and it will be understood 85 that the eye 11 is engaged with the eye 6 before the arms are passed through the sleeve. These arms are of greater length than the sleeve and have their free ends projecting from one end of the sleeve and coiled about 90 each other to form a flat head or abutment 13 which bears against the end of the sleeve about the opening thereof through which the arms pass and will serve very effectively to 95 prevent the sleeve from slipping off the core. 100

It should be noted that the anchor bar is of greater diameter than the width of the slot 5. Therefore, this anchor bar cannot move inwardly through the slot and when the portion 7 of the back-band is drawn tightly about the anchor bar the hook will be securely held in a set position upon the band. Instead of having the ends of the arms coiled about each other to form a flat head, the arms 10 may be only of sufficient length to project a short distance from the free end of the sleeve and these end portions bent, as shown at 14 in Fig. 6, to engage the sleeve and retain the sleeve in place about the core. It should also 15 be noted that if the ends are to be bent apart as shown in Fig. 6 the core may be formed of a strand of wire which is circular in cross section, but it will preferably be in the form of an elongated cotter key having its arms 20 formed with flat contacting side faces as shown in Fig. 7.

In Figure 5, there has been shown a modified construction wherein the sleeve of the anchor bar instead of being tubular as shown 25 in Figures 2 and 4 consists of a strand of resilient wire coiled to form a sleeve 15 which has convolutions throughout its length and is yieldable longitudinally so that when the arms of the core are passed through this sleeve 30 and bent to form the head 13 the sleeve will have binding engagement with the eye 11 and abutment head 13. Since the sleeve 15 consists of a coiled wire and has convolutions 35 throughout its length, a very good gripping action will take place between the anchor portion and the portion 7 of the back-band through which this bar is passed. In either construction the back-band may be drawn 40 outwardly through the slot 5 a sufficient distance to permit the anchor bar to be swung from the operative position shown in Figures 1 and 2 to the position shown in Figure 3, thereby permitting the hook to be bodily detached from the back-band when repairs or 45 replacements are necessary.

In Figure 8, there has been shown another modified form of anchor bar. In this construction one end portion of a wire strand forms a core 16 which is straight and extends 50 throughout the length of the bar. After determining the proper length for the core the wire-strand is passed through the eye 6 and then bent to form an eye 17 corresponding to the eye 11 and the wire is then coiled about 55 the core 16 to form a sleeve 18 which extends slightly beyond the free end of the core and is tapered slightly at its free end, as shown at 19. The tapered end of the sleeve prevents the free end of the core 16 from projecting beyond the sleeve and prevents danger 60 of a person cutting his hands when adjusting the hook upon the back-band.

It should also be noted that if it is desired, the anchor bar may be formed solid 65 and carry an eye at one end for engagement

with the eye 6 or a flexible element such as a string may be used to loosely connect one end of the anchor bar with the body and be secured to the anchor bar and body in any manner desired. 70

Having thus described the invention, I claim:

1. A back-band hook comprising a body, a bill carried by said body and facing upwardly, a slot being formed transversely in said body above the upper end of said bill, an eye at one end of said slot, and an anchor bar movable into and out of position to extend longitudinally of said slot in front thereof, said anchor bar consisting of a sleeve, and a core extending through said sleeve and having an eye at one end loosely engaged with the eye of said crosshead, the other end of the core projecting from the sleeve and formed into a head to retain the sleeve upon the 85 core.

2. A back-band hook comprising a body, a bill carried by said body and facing upwardly, a slot being formed transversely in said body above the upper end of said bill, an eye 90 at one end of said slot, and an anchor bar movable into and out of position to extend longitudinally of said slot in front thereof, said anchor bar consisting of a sleeve, and a core extending through said sleeve and 95 formed from a strand bent intermediate its length to form an eye engaged with the eye of said crosshead and arms extending through the sleeve with their free ends projecting therefrom and bent to form a head 100 adapted to retain the sleeve in place about the arms.

3. A back-band hook comprising a body, a bill carried by said body and facing upwardly, a slot being formed transversely in said body above the upper end of said bill, an eye 105 at one end of said slot, and an anchor bar movable into and out of position to extend longitudinally of said slot in front thereof, said anchor bar consisting of a sleeve, and a 110 core extending through said sleeve and formed from a strand bent intermediate its length to form an eye engaged with the eye of said crosshead and arms extending through the sleeve with their free ends projecting therefrom and wrapped about themselves to form a flat head of greater diameter than the passage through the sleeve and adapted to engage the end of the sleeve about the passage and retain the sleeve in place. 115

4. A back-band hook comprising a body formed with a transversely extending slot and having a bill disposed below the slot, an eye at one end of said slot, and an anchor bar movable into and out of an operative 125 position longitudinally of the slot in front of the body and consisting of a sleeve, and a core for said sleeve loosely engaged with the eye and extending through the sleeve with its other end projecting from the sleeve and 130

formed with an abutment to retain the sleeve in place about the core.

5. A back-band hook comprising a body formed with a transversely extending slot and having a bill disposed below the slot, an eye at one end of said slot, and an anchor bar movable into and out of an operative position longitudinally of the slot in front of the body and consisting of a sleeve, and a core for said sleeve consisting of a strand bent intermediate its length to form an eye engaged with the eye of said body and arms extending through the sleeve with their free ends projecting from the sleeve and twisted to form a head engaging the end of the sleeve to retain the sleeve in place about the core.

6. A back-band hook comprising a body formed with a transversely extending slot and having a bill disposed below the slot, an eye at one end of said slot, and an anchor bar movable into and out of an operative position longitudinally of the slot in front of the body and consisting of a sleeve formed from a strand coiled to form a sleeve having circumferentially extending convolutions and yieldable longitudinally, and a core for said sleeve having one end loosely engaged with the eye and extending through the sleeve with its other end projecting from the sleeve and formed with an abutment to retain the sleeve in place about the core.

7. A back-band hook comprising a body formed with a transversely extending slot and having a bill disposed below the slot, an eye at one end of said slot, and an anchor bar movable into and out of an operative position longitudinally of the slot in front of the body and consisting of a sleeve formed from a strand coiled to form a sleeve having circumferentially extending convolutions, a portion of the strand being bent to form an attaching eye at one end of the coil, and a core extending from the eye through the coil axially thereof.

45. 8. A back-band hook comprising a body formed with a transversely extending slot and having a bill disposed below the slot, an eye at one end of said slot, and an anchoring bar having one end loosely connected with said eye to mount the bar for swinging movement into and out of an operative position longitudinally of the slot in front of the body, the bar being of greater diameter than the slot to prevent movement thereof through the slot.

In testimony whereof I affix my signature.
LLOYD L. WEAKLEY. [L. s.]
